Inventor

Nathan Rose

United States Patent Office.

NATHAN ROSE, OF BELMONT, NEW YORK.

Letters Patent No. 92,370, dated July 6, 1869.

IMPROVEMENT IN PICKS.

The Schedule referred to in these Letters Patent and making part of the same.

To all whom it may concern:

Be it known that I, NATHAN ROSE, of Belmont, in the county of Allegany, and State of New York, have invented certain new and useful Improvements in Picks; and I do hereby declare that the following is a full, clear, and exact description thereof, reference being had to the accompanying drawings, and to the letters of reference marked thereon, which form a part of this specification, and in which—

Figure 1 represents a perspective of the holder;

Figure 2, a perspective, with the pick removed;

Figure 3, a perspective, with the clamp opened;

Figure 4, a perspective, showing one side of the holder;

Figure 5, a perspective, showing the other side of the holder;

Figure 6, a perspective of the clamp; and

Figure 7, a perspective of the holder, with the pick and clamp removed.

Similar letters indicate like parts in all the figures.

My invention relates to improvements in pick-holders, and to this end

It consists in the method of adjusting and supporting the end of the pick in the holder, so that every blow upon the pick tightens the same in the holder; all of which will hereinafter be fully set forth.

To enable others skilled in the art to which my invention appertains to make and use the same, I will now describe its construction and operation.

In the accompanying drawings—

A represents the holder, made in the shape of a wedge;

b b represent a mortise, cut in each opposite face of the holder; and

b', a mortise cut in the centre of the holder, connecting the two mortises *b b'*.

D represents the clamp, made as seen in fig. 6, and pivoted in the mortise *b'*, and working upon the principle of a pair of tongs.

E is the pick, inserted in the blunt end of the holder, as seen in fig. 1.

By this arrangement any sized pick can be used with the holder described; and, also, the more the pick is used the firmer it is held in the holder.

Having thus described my invention,

What I claim as new, and desire to secure by Letters Patent, is—

1. The holder A, constructed as described, and provided with the hinged clamp D, substantially in the manner and for the purpose described.

2. A pick-holder, consisting of the holder A, provided with mortises *b b'* and pick E, all constructed, arranged, and operating substantially in the manner and for the purpose specified.

In testimony that I claim the foregoing as my own, I affix my signature, in presence of two witnesses.

NATHAN ROSE.
